UNITED STATES PATENT OFFICE.

JOHN CLARK, OF GREENVILLE, CALIFORNIA.

AUTOMATIC GATE.

SPECIFICATION forming part of Letters Patent No. 337,556, dated March 9, 1886.

Application filed August 5, 1885. Serial No. 173,604. (Model.)

To all whom it may concern:

Be it known that I, JOHN CLARK, of Greenville, in the county of Plumas and State of California, have invented a new and Improved Automatic Gate, of which the following is a full, clear, and exact description.

My invention relates to automatic or self opening and closing gates, and has for its object to improve their construction and operation, so as to make them inexpensive, efficient, and durable.

The invention consists in certain novel features of construction and particular combinations of parts of the gate, all as hereinafter fully described and claimed.

Reference is to be had to the accompanying drawings, forming part of this specification, in which similar letters of reference indicate corresponding parts in all the figures.

Figure 1 is a side elevation of my improved gate, with parts broken away and in section. Fig. 2 is a plan view in section on the line 1 1, Fig. 1, with one of the platforms partly removed. Fig. 3 is a vertical transverse sectional elevation, partly broken away, and taken on the line 2 2, Fig. 1. Fig. 4 is a transverse vertical section taken through the gate-platform, and on the line 3 3, Fig. 1. Fig. 5 is a like view taken on the line 4 4, Fig. 1; and Figs. 6, 7, and 8 are detail views of the swing-post of the gate, with the guide-head which works in the double cam-groove of the post shown in three different positions.

The gate proper is made with a vertical swing-post, A, next the hinge-post B, and an outer post, A', next the latch-post C, said posts A A' being connected by rails a and braces a', so as to constitute a strong structure adapted to swing with the post A, which has a long axial pin, a², at its upper end, said pin a² passing loosely through the plate B', fixed to the head of hinge-post B, and at its lower end the post A has a pin or stud, a³, which enters a hole in the outer end of a lever, D, or in a metal plate or arm fixed to said lever.

The hinge-post B is formed of two side pieces, b b, which are secured to each other at the upper end and diverge toward their lower ends, where they are connected one to each of the pair of sill-beams E E, which rest on the

ground, and between the side pieces b b of post B is secured a plate or board, b', which supports a gate-lock, hereinafter described.

The latch-post C is made of two downwardly-diverging side pieces, c c, connected with each other at the top, and to the sills E E at the bottom, or in A form, and substantially like the post B, and between the sides c c is secured a plate, c', to which the gate-latch devices, presently described, are attached. Suitable spacing-blocks, e e, are provided between the opposite ends of the sills E E, which are secured to these blocks to form a substantial support to the posts B C, and to the lever mechanism of the gate and to the sills E E are secured at right angles the cross bars or beams F F, which for a double gate extend opposite ways from the sills, and with them rest on the ground and form part of the foundation or support of the gate and prevent the gate from tipping over sidewise.

To the outer ends of the beams F F are fixed the bars G G, which range parallel with the gate—one at each side of it—and have fixed to their upper faces the bars or stringers G', which are rabbeted at the under side along the inner edge to admit the outer ends, i, of the cleats or cross-bars I', to which the floors I are secured, said floors I constituting platforms, which, by the outer ends, i, of their cleats I', have a hinging or loose connection with the bars G G', while the inner edges or parts of the opposite platforms, I, nearly meet directly under the closed gate and rest on a system of levers, next described.

The lever D, to which the lower end of the swing-post A is journaled, as above mentioned, is pivoted at d to and between the sills E E, and on the end of the short arm d' of lever D rests the lever H, which is pivoted at h to blocks attached to the sills E E, near the latch-post C. Springs J are attached at their outer ends to the under sides of the two cleats I', nearest the latch-post C of each platform I, and by their free ends rest on the top of the lever H, to which they may loosely be held by a pin-and-slot connection, (see Figs. 1 and 4,) and which construction allows the end i' of the inner part of each platform I to be lowered against the tension of its springs J independ-

100

ently of the lowering of the end part, i' , of the other platform, and for purposes presently explained.

To the two cleats I' of each platform I, next to the swing-post A, are fixed at their one ends straps or plates K, preferably made of sprung metal, and which project from opposite sides across the opening between the two platforms at that end, and keep these ends of the platforms always about level at their upper faces. (See Figs. 1, 2, and 5.)

To a pin, l , passed through the lever H, are pivoted, one at each side of said lever and parallel with it, the levers L L', which are connected, preferably by the elastic bars or plates L', with the opposite ends of a rock-arm, M, which is fixed at its center to a short shaft, m, journaled in a lug, m' , and in a bent plate, m^2 , both lug and plate $m'm^2$ being secured to the end of the lever H nearest the swing post A, and so that a guide-head, N, fixed to the outer end of the shaft m, may enter the upper portion, o, of a double-curved cam slot, O, formed by the opposite diverging grooves, $o' o^2$, which converge at the groove part at o and extend downward therefrom and around the swing-post A for about one-quarter the circumference of the post. The elastic connection-bars L' exert their tension at opposite ends of the rock-arm M, to maintain the guide-head N, which preferably is pointed at both ends, and necessarily at the lower end, in the position shown in Fig. 6, or aligned with the part o of the cam-slot O when no pressure is on the platforms I; but when the pressure is brought on the platforms (by a horse's fore feet, for instance) a pin, P, fixed in the platform, will be pressed down onto the short arm of the corresponding lever, L, which will have the effect to throw the other end of the lever upward and rock the arm M, so that the pointed lower end of the head N will be turned in the part o of the slot O, which end stands normally in the plane of the gate, and cause the head N to enter one of the curved parts of the slot O as the gate is lifted by the levers H D, when the platforms I are carried down by the weight of the horses stepping on them. The head N always will be turned so as to enter that side or portion o' or o^2 of slot O next the platform onto which pressure first is exerted to cause the gate always to open from the advancing animals, which are to pass through the gateway, and as hereinafter more fully explained.

I form the cam-slot O in a metal plate, or between metal plates, fixed to the swing-post to insure increased durability against the frictional contact of the head N with the side walls of the slot. The three sided shape of the bent end bearing-plate m^2 on the lever H makes it self-bracing against the lateral pressure either way of the shaft m of head N as the gate is opened, and short posts H' H' rise from the sills E at opposite sides of the lever H, to prevent sidewise displacement of the lever by

the lateral strains induced by operating the gate.

The end portions, $i' i'$, of both of the platforms I are connected by chains or cords R with an open loop or ring, r, fixed to the outer end of the long arm of an elbow-lever, S, which is pivoted at its angle s to lugs on a metal plate fixed to the part c' of the latch-post C, and the short arm of the lever S has a pin or stud, s', which, when either of the platforms is lowered at i' , is moved outward against the angle of the spring-latch T to withdraw its end t from a slot or opening in a catch-plate, T', fixed to the post A' of the gate, and prior to the swinging open of the gate by the action of the levers under the platforms.

To the plate or board b' of the hinge-post B is fixed at one end the spring-metal lock-bar U, which has a bent end portion, u, which passes through the board b', and when in normal position extends above a lug, u', fixed to the swing post A, and so as to prevent lifting of said post and the gate, except when the end u of lock-bar U is drawn back, which may be done by drawing on chains or cords U', which are connected to one arm of an elbow-lever, V, pivoted to the post-plate b', and having a pin or stud, v, on its other arm, which projects inside of the lock-bar at its bend and draws its end part u outward.

For convenience in operating the lock-bar U the pull chains or cords, after passing over pulleys u^2 at the top of post B, run to pulleys w on the posts W W, set at the side of the road at opposite sides of the gate, so that a person on horseback or in a vehicle may draw on the pull-cords to draw back the lock-bar V just as the horse or horses step onto one of the platforms I, and without requiring the person to dismount or to alight from the vehicle.

It will be seen from Figs. 1, 4, and 5 that in the normal positions of the opposite platforms I their ends i^2 , to which the plates K are attached, rest on or close to the upper part of the inclined lever H, while the opposite ends of the platforms are held some little distance above the fulcrumed end of said lever by the springs J, so that said springs instantly will yield to permit the end parts i' of the platforms to be lowered first by pressure on the platforms.

The operation of the gate is as follows: Should the team approach the gate in direction of arrow x in Fig. 3, the pressure of their fore feet on the right-hand platform I will depress the end part i' of said platform against the tension of its springs J, and the latch-chain R will be drawn upon to pull back the latch T, the cord U' having been drawn upon to draw the end u of lock-bar U back from the stud u' on post A, to permit the post to rise, and simultaneously with the pulling back of the latch T the pin P of the right-hand platform I strikes the top of the short arm of the corresponding lever, L, so its arm L' tilts the arm M up at that side to turn the head N from

its normal position (shown in Fig. 6) to the position shown in Fig. 8, and so its lower end will enter the part o' of cam-slot O, as both the platforms I are fully depressed, and the 5 descending platforms will lower the lever H and carry the head N downward into the cam-slot at o' at the same time that the pressure of lever H on the lever D will lift the swing-post A and the gate as the shaft a^2 of post A 10 slips through the bearing-plate B, and the action of the head N in the part o' of cam-slot O will swing the gate open from the horses as it rises, or toward the left hand. When the team approaches the gate from the other side, or 15 in direction of the arrow y, in Fig. 3, the arm M will be rocked by the pressure of the left-hand platform by its pin P on the corresponding lever, L, and will cause the head N to be moved as indicated in Fig. 7, so that the head 20 will enter the part o^2 of the cam-slot O to cause the gate to be swung from the horses, or toward the right hand, as the gate is lifted by the levers H D, as will be readily understood. When the horses and vehicle have passed 25 through the gateway from either side, the gate will swing shut by its own weight and will automatically be latched by latch T and locked by bar U, as above explained, and the head N will pass into the part o of cam-slot O as the 30 gate settles down and will be held in central normal position, as in Fig. 6, by the elastic arms $L' L'$ of levers L L, until either one of the platforms I is pressed down, as above described.

35 I do not limit myself to the precise construction of the gate-latch devices herein shown and described, as they may be otherwise arranged so as to cause the gate to unlatch by pressure on the platforms.

40 I have shown and described the gate as constructed with two platforms, I, one at each side of the gate; but it is evident that in many situations but one platform, I, at one side of the gate may be used, in which case the levers L, their arms L' , and the rock arm or bar M may be dispensed with, and the cam-head N, journaled on lever H, will act in a cam-groove in post A, curving downward toward the side from which the gate is to open.

45 Having thus described my invention, I claim as new and desire to secure by Letters Patent—

1. An automatic gate comprising the gate proper, provided with a swing-post, A, having axial support at its upper end from the 55 hinge-post B, and at its lower end in one of a system of levers pivoted in the gate-sills, and said post A provided with an inclined or cam groove, a platform or platforms adapted to be depressed and resting on the levers, and 60 a head, N, held to one of the levers and adapted to the cam-groove in post A, substantially as shown and described, whereby the gate may be lifted and opened by depressing the platform, and will swing shut by gravity, as 65 set forth.

2. An automatic gate comprising the gate

proper, provided with a swing-post, A, having axial support at its upper end from the hinge-post B, and at its lower end in one of a system of levers pivoted in the gate-sills, 70 and said post A provided with an inclined or cam groove, a platform, or platforms adapted to be depressed and resting on the levers, a head, N, held to one of the levers and adapted to the cam-groove in post A, substantially as shown and described, whereby the gate may be lifted and opened by depressing the platform, and will close by gravity, and said platform or platforms arranged to yield or fall first at one end, in combination with a device, substantially as described, for latching the gate, and connected to the platform so as to be unlatched as the platform falls at that end, substantially as herein set forth. 85

3. An automatic gate comprising the gate proper, provided with a swing-post, A, having axial support at its upper end from the hinge-post B, and at its lower end in one of a system of levers pivoted in the gate-sills, 90 and said post provided with an inclined or cam groove, a platform or platforms adapted to be depressed and resting on the levers, a head, N, held to one of the levers and adapted to the cam-groove in post A, substantially 95 as described, whereby the gate may be lifted and opened by depressing the platform, and a locking device, substantially as described, on the hinge-post B, and adapted to prevent the lifting and opening of the gate, substantially as herein set forth. 100

4. In an automatic gate, the combination, with the gate proper, its post A, provided with a double-inclined cam-groove, O, and the hinge-post B, of the levers D H, pivoted 105 in the gate-sills, hinged platforms I I, resting on the levers, springs J, normally supporting the ends i' of the platforms, so said ends first will yield to pressure-levers L L, pivoted to lever H, a head, N, journaled by 110 its shaft m on lever H, and adapted to the slot O of post A, a rock-arm, M, on shaft m , bars or plates $L' L'$, connecting arm M with levers L L, and pins P P at the first yielding ends of the platforms, and adapted to tilt levers L L, arm M, and head N as the platform is depressed, substantially as herein set forth. 115

5. The double gate-platforms I I, held to the sill-frame at their outer ends or sides, plates or straps K K, lapping the joint between the opposite platforms, I I, to mutually support them at one end and cause their depression in unison at that end, and springs J under each platform at their ends i' , to allow this end of each platform first to yield 120 under pressure, in combination with a system of levers pivoted in the gate-sills and supporting the platforms yieldingly, and a head, N, on one of the levers, and acting in a cam-slot in the gate-post to swing the gate as it is 125 lifted by the levers, substantially as herein set forth. 130

6. In automatic gates, the gate proper, its post A, having a cam-groove, a platform or platforms supported on a system of levers having a head, N, adapted to the cam-groove of post A, and one end, i', of said platforms arranged to yield first to pressure, in combination with a latch device consisting of a latch-bar, T, and an unlatching-lever, S, and a connection, as at R, between lever S and the platform, substantially as herein set forth.
7. In automatic gates, the gate proper, its post A, having a cam-groove, a platform or

platforms supported on a system of levers having a head, N, adapted to the cam-groove of post A; and said parts coacting to raise and open the gate as the platforms are depressed, in combination with a lock device consisting of a lock-bar, U, and an unlocking-lever, V, said bar U adapted to a stud on the gate-post A, substantially as herein set forth.
